UNITED STATES PATENT OFFICE.

JESSE EDWIN GROSS, OF FORT WAYNE, INDIANA, ASSIGNOR TO WALTER F. ROSEN-WINKEL, OF FORT WAYNE, INDIANA.

TABLE ATTACHMENT FOR AUTOMOBILES.

1,403,317.

Specification of Letters Patent. Patented Jan. 10, 1922.

Application filed March 5, 1921. Serial No. 449,764.

To all whom it may concern:

Be it known that I, JESSE EDWIN GROSS, a citizen of the United States of America, and resident of Fort Wayne, in the county 5 of Allen and State of Indiana, have invented certain new and useful Improvements in Table Attachments for Automobiles, of which the following is a specification.

This invention relates to improvements 10 in table attachments for automobiles and is intended especially to be positioned in the tonneau and secured in supported connection with the robe-rail that usually extends from the back of the front seat. The object 15 of the invention is to provide a table that may be folded up into compact form, and when in use may be rigidly positioned in the tonneau of an automobile and the robe-rail utilized as a support therefor. Another 20 object of the invention is to so construct the table that it will be equally applicable for connection with a rope or chain that is sometimes employed for suspending a robe in automobiles, as well as a robe-rail.

25 The objects of the invention are accomplished by the construction illustrated in the accompanying drawings in which:

Fig. 1 is a side elevation of a table embodying the invention and including a robe-rail to which it is attached, the robe-rail being in section; and

Fig. 2 is a bottom plan view of the table in folded position.

The characters of reference hereinafter 35 appearing have reference to the parts designated on the drawings by similar characters:

The invention consists of a table comprised of a top proper 1, to one side of 40 which is secured a folding leaf 2 by means of hinges 3 that admit of the leaf being swung so as to fold under the top proper. To the underside of the top proper, near the side thereof opposite the leaf is secured 45 a folding support 4 by means of hinges 5, the support being arranged parallel with the side of the top. In the lower edge of the support 4 is a V-shaped groove 6, and at each end of the support adjacent the top 50 is an extension 7 in which is secured an eye 8 and corresponding hook 9. Also, the

support has on its side opposite its hinges a hook 10 adapted to engage in an eye 11 secured to the top 1 and hold the support 4 in erect position.

To the underside of the top proper is pivoted a beam 12, by means of a screw 13, that is adapted to be turned upon its pivot so as to extend out beneath the leaf 2 when the latter is in extended position and support the same. To the outer end of the beam 12 is secured a folding leg 14 by means of a hinge 15, the leg being adapted to be folded flat against the bottom of the beam. The leg has movably arranged therein an extension leg 16 adapted to be held in adjusted positions by a thumb-screw 17 in the leg 14. The inner end of the beam 12 has a slot 18 made therein for the reception of the projecting thumb-screw 17 when the leg 14 is in folded position to admit of the leg being folded flat against the beam.

In Fig. 1 the table is shown erected with the support 4 positioned upon the robe-rail 19 which is horizontally disposed and which is fixedly positioned in the rear of the front seat 20 upon the usual brackets 21, the rail extending partially in the groove 6 of the support, and the hooks 9 holding the rail and support 4 detachably together. The beam 12 is positioned so as to support the leaf 2 in the plane of the top 1, and the leg is positioned for supporting the bottom so that the table is held horizontally for use.

In Fig. 2 the beam 12 is turned lengthwise so as to admit of the support 4 and leaf 2 being folded flat against the underside of the top proper, and the leg 14 is folded flat upon the bottom of the beam. When thus arranged the device is in compact form suitable for storage.

What I claim is:

1. In a tonneau table, a top having a folding leaf at one side thereof; a folding supporting member secured to the underside of the top near the side thereof opposite the leaf and having means in connection therewith for detachably securing it to the robe-rail of an automobile; a beam having pivotal connection with the top beneath the under side thereof adapted to be positioned so as to support the leaf in the plane of

the top; and a folding leg in connection with the beam for its support.

2. In a folding table for automobiles, a top; a supporting member hinged to the underside of the top and having a groove in its lower edge for the robe-rail of the automobile and means for detachably securing the member thereon, and having also means for securing the supporting member to the

top in erect position; and folding means in connection with the top for supporting the same horizontally.

In testimony whereof I affix my signature in presence of two witnesses.

J. EDWIN GROSS.
